CLAIM

The ornamental design for a safety relay, as shown and described.

DESCRIPTION

FIG. 1 is a front elevational view of the relay;

FIG. 2 is a rear elevational view thereof;

FIG. 3 is a top elevational view thereof;

FIG. 4 is a bottom elevational view thereof;

FIG. 5 is a right side elevational view thereof;

FIG. 6 is a left side elevational view thereof; and,

FIG. 7 is a front and left side perspective view thereof.

The broken line portion of the figure drawings is included to show unclaimed subject matter only and forms no part of the claimed design.
